UNITED STATES PATENT OFFICE

LEE G. VOORHEES, OF LONG ISLAND CITY, NEW YORK, ASSIGNOR TO NATIONAL
CARBON COMPANY, INC., A CORPORATION OF NEW YORK

FOCUSING FLASHLIGHT

Application filed July 23, 1927. Serial No. 207,919.

This invention relates to electric hand lamps of the type having a bulb, a reflector, and a battery within a single casing, and more particularly to the method of mounting the bulb and reflector within the casing, and to the method of securing relative movement between them.

Focusing hand lamps in which the bulb and reflector may be moved relatively to one another are well known and may be divided into two classes: the first, including those in which the bulb is moved relatively to a fixed reflector and; the second, including those in which the reflector is moved relatively to a fixed bulb. The difference between the hand lamps of the two classes is chiefly in the method of securing the result.

In hand lamps of the first class, the bulb is usually carried by a socket that slides in a sleeve attached to the apex of the reflector. The bearing between the socket and the sleeve is usually so short, and the clearance between them so great, that the lamp may tip sidewise until its filament is farther from the focal point of the reflector than it might be in a non-focusing hand lamp.

In hand lamps of the second class, the bulb is usually carried by a socket attached to a diaphragm which in turn is secured to the casing, and the reflector is carried by a head fitting that screws over the end of the casing. As the bulb moves through a clearance opening in the apex of the reflector there is consequently no direct connection between the bulb and the reflector to insure their correct alignment. Therefore, in this class of hand lamp also, the focusing movement may be incapable of bringing the bulb filament into coincidence with the focal point of the reflector.

The direction of the focusing movement is usually along the axis of the reflector and to be effective the reflector and the bulb must be in axial alignment. In some instances such is not the case, as has been already pointed out, consequently, the axial misalignment defeats the purpose of the focusing adjustment in most hand lamps.

Therefore, one of the objects of this inven-

tion is to provide a means of securing axial focusing adjustment between the bulb and the reflector of a hand lamp and, at the same time, to hold them in axial alignment. How this and other objects and aims of the invention are accomplished will be readily understood from the following description when taken in connection with the illustration which shows a sectional view of a hand lamp embodying this invention.

In the drawing 13 designates the usual cylindrical casing which may be either of insulating material, such as fiber, or of conductive material, such as brass or iron. Within the casing 13 is the usual battery 15 composed of two or more dry cells placed end to end and connected in series by being held in contact with each other by the conductive battery supporting spring 18 seated within the end cap 17 which is threaded to the casing 13 in the usual manner. Resting against the top of the casing 13 is a disk 7 which is preferably of insulating material, such as fiber, and is approximately the same outer diameter as the casing. Fitting closely around both the casing 13 and the disk 7 is a collar 4 which is secured to the casing 13 by the rivets 5. The upper edge of the collar 4 is turned inward forming the flange 4' which rests against the disk 7 thereby securing it to the casing 13.

Upon the upper side of the disk 7 is the lamp socket 19 having a cylindrical portion 19' threaded both inside and outside and a flangelike portion 19'' which is attached to the disk 7 by the rivets 8. Within the lamp socket 19 is the usual lamp bulb 11. Passing through the central portion of the disk 7 is the rivet or eyelet 6 which connects the central terminal of the bulb 11 to the central terminal of the battery 15.

Threaded upon the outside of the socket 19 is a bushing 3 which is secured in an opening 12' in the apex of the reflector 12 but is insulated therefrom by the insulation 2. In some cases the bushing 3 and the insulation 2 may be eliminated by turning the edge of the reflector opening 12' downward and threading it to fit the outside of the lamp socket 19.

The cover glass 10 and the reflector 12 are secured to the upper end of the head 20 by the

bezel 9 in the usual manner. At the bottom of the head 20 is a cylindrical projection 20' surrounding and slidably mounted on the collar 4 thereby supporting the head 20 upon the casing 13 but permitting rotary and axial movement between the head 20 and the collar 4 which forms a part of the casing 13. Thus the reflector assembly comprising the reflector 12, bushing 3, cover glass 10, bezel 9, and head 20, is adjustably mounted upon the lamp socket 19 and movably mounted upon the casing 13. A switch 16 mounted upon the outside of the casing 13 completes the circuit through the battery 15 and the lamp 11 by means of the conductors 14 in the usual manner.

Focusing movement is secured by rotating the reflector assembly as a unit upon the casing. As it rotates its threaded relation with the lamp socket 19 causes it to move axially of both the bulb 11 and the casing 13. As the reflector assembly is threaded directly to the lamp socket relative radial movement between the bulb and reflector cannot occur, and as the reflector assembly is supported upon the casing relative tilting between the bulb and reflector is effectively prevented. Thus the bulb and reflector are held in axial alignment throughout the range of the focusing movement.

I claim:

1. In an electric hand lamp, the combination of a casing having a battery therein; a disk resting upon one end of said casing; a flanged collar securing said disk to said casing; a threaded lamp socket secured to said disk; a reflector having an aperture threaded upon said lamp socket; a head fitting movably mounted upon said collar; a cover glass over the open end of said reflector; a bezel securing said cover glass and said reflector to said head fitting; a lamp in said lamp socket; a conductive rivet in said disk connecting one terminal of said lamp to one terminal of said battery; and means completing the circuit from the other terminal of said lamp to the other terminal of said battery.

2. In an electric hand lamp, the combination of a casing; a disk attached to one end thereof; a lamp socket mounted upon said disk; a reflector threaded upon said lamp socket; a head fitting rigidly secured to said reflector and movably mounted upon said casing; a lamp in said socket; a battery within said casing; and means completing the circuit through said lamp and said battery.

3. In an electric hand lamp, the combination of a casing; a disk mounted upon one end thereof; a lamp socket mounted upon said disk; a reflector threaded upon said lamp socket; and a head fitting rigidly secured to said reflector and movably mounted upon said casing.

4. In an electric hand lamp, the combination of a casing; a disk resting upon one end

thereof; a collar securing said disk to said casing; a lamp socket mounted upon said disk; a reflector threaded upon said lamp socket; and a head fitting rigidly secured to said reflector and movably mounted upon said collar.

5. In an electric hand lamp, the combination of a casing; a disk resting upon one end thereof; a collar mounted upon said casing and having an inturned flange securing said disk to said casing; a lamp socket mounted upon said disk; a reflector adjustably mounted upon said lamp socket; a head attached to said reflector and movably mounted upon said collar; a lamp in said lamp socket; a battery in said casing; and means completing the circuit through said lamp and said battery.

6. In an electric hand lamp, the combination of a casing; a disk mounted upon one end thereof; a lamp socket mounted upon said disk; a bushing adjustably mounted upon said lamp socket; a reflector rigidly secured to said bushing; and a head rigidly attached to said reflector and movably mounted upon said casing.

7. In an electric hand lamp, the combination of a casing; a disk mounted upon one end thereof; a lamp socket mounted upon said disk; a bushing adjustably mounted upon said lamp socket; a reflector rigidly secured to said bushing but insulated therefrom; a head rigidly attached to said reflector and movably mounted upon said casing; a lamp in said socket; a battery in said casing; and means completing the circuit through said battery and said lamp.

8. In an electric hand lamp, the combination of a casing; a lamp socket rigidly mounted upon one end thereof; a lamp bulb in said lamp socket; a reflector assembly comprising a head, cover glass, bezel, and reflector threaded upon said lamp socket and movably mounted upon said casing; a battery within said casing; and means completing the circuit through said lamp and said battery.

In testimony whereof, I affix my signature.

LEE G. VOORHEES.
